UNITED STATES PATENT OFFICE

ALMOND W. PIPER, OF NEWPORT, MAINE

VALVED CLOSURE FOR LIQUID CONTAINERS

Application filed October 16, 1930. Serial No. 489,166.

This invention relates to oil stoves or ranges of that type embodying a reservoir from which the oil flows to the burners, and an oil container which is in the form of a large bottle and is arranged in an inverted position on and discharges into the reservoir.

The invention relates more particularly to the oil container, and has for one of its objects to provide for a container of this character a closure which will prevent the oil from spilling while applying the container to the reservoir and which will automatically open on the application of the container to the reservoir so as to permit the oil to flow therefrom to the reservoir.

The invention has for a further object to provide a closure of the character stated which shall be adapted to permit the oil to flow from the container to the reservoir without noise and which shall be adapted to prevent any foreign matter in the oil from flowing from the container to the reservoir.

The invention has for a further object to provide a closure of the character stated which shall be adapted to prevent oil from dripping from the container while it is being removed from the reservoir.

The invention has for a still further object to provide a closure of the character stated which shall be simple, durable and highly efficient, which may be manufactured and sold at a comparatively low cost, and which may be readily applied to the container.

The invention is hereinafter fully described and claimed, and illustrated in the accompanying drawing, wherein:—

Figure 1 is a view in side elevation of an oil stove or range reservoir and container of which the latter is equipped with a closure constructed in accordance with my invention.

Figure 2 is a view in side elevation of the closure, and

Figure 3 is a sectional view taken on the vertical plane indicated by the line 3—3 of Figure 1.

Referring in detail to the drawing, 1 designates the reservoir and 2 the container of an oil stove or range. The reservoir 1 is se-

cured to the pedestal 3 of a stand, and is connected by a pipe 4 to the burners, not shown, of the stove or range. The container 2 is in the form of a large bottle, and is arranged in an inverted position on the reservoir 1 with the lower end of its neck 5 extending into the reservoir. The container 2 is supported from the pedestal 3 by a clamp 6. The oil flows from the container 2 into the reservoir 1, and flows from the reservoir by means of the pipe 4 to the burners of the stove or range. As these parts are of well-known construction, a further description thereof is deemed unnecessary.

The container 2 is provided with a closure 7 which comprises a cap 8 which is applied to the discharge end of the neck 5. The annular wall 8a of the cap 8 is provided with screw threads 9 which engage screw threads 10 on the neck 5 to removably secure the cap in applied position. The circular wall 8b of the cap 8 is provided with an axial opening 11 through which extends a tube 12. The outer portion 12a of the tube 12 is smaller in external diameter than the inner portion 12b thereof, and said outer portion has a snug fit in the opening 11. A shoulder 13 formed at the juncture of the tube portions 12a and 12b contacts with the inner surface of the cap wall 8b. The inner end of the tube 12 is formed to provide a conical seat 14 for a conical valve 15, and the tube is provided near its outer end with radial ports 16.

The valve 15 is carried by the inner end of a stem 17 which is longer than and extends through the tube 12. The stem 17 is smaller diametrically than the corresponding inner dimension of the tube 12, so as to permit the oil of the container 2 to flow through the tube 12 when the valve 15 is unseated. The stem 17 is provided at its outer end with a reduced extension or stud 18 and mounted upon the stud and secured thereto by a pin 19 is a circular head 20 which is larger diametrically than the corresponding external dimension of the tube 12. A coil spring 21 which surrounds the outer tube portion 12a and bears at its inner end against the cap wall 8b and at its outer end against the head 20, constantly

tends to urge the valve 15 in the direction of its seat 14.

A cylindrical screen 22 surrounds the tube portion 12b and extends inwardly therefrom. The tube 12 may be secured to the cap wall 8b by solder or in any other suitable manner, and this solder or the like 23 may be employed to secure the screen 22 to the tube. The screen 22 surrounds the seat 14 and valve 15, and the inner end 24 thereof is of solid formation.

In practice, the container 2 is filled with oil, and thereafter the closure 7 is applied to the container. Until the container 2 is applied to the reservoir 1, the spring 21 holds the valve 15 against its seat and in view thereof the oil will not spill from the container during the application of the container to the reservoir. During the application of the container 2, the head 20 contacts with a plug 25 on the bottom wall of the reservoir 1 and moves the stem 17 inwardly against the tension of the spring 21, with the result that the valve 15 is moved inwardly or off of its seat 14, and thus permitting the oil to flow from the container by way of the passage between the tube 12, and stem 17 and the openings 16 in the tube into the reservoir 1. The screen 22 prevents any foreign matter in the oil from flowing from the container 2 into the reservoir 1. As the valve seat 14 is located inwardly beyond the cap wall 8b, a trap 26 is provided for the foreign matter. The solid inner end 24 of the screen 22 causes the oil to enter the screen from the sides thereof, and due thereto the oil is divided into such fine streams that its passage from the receptacle 2 to the reservoir 1 will be noiseless. While the receptacle 2 is being lifted from the reservoir 1, the spring 21 will react and move the valve 15 on to its seat 14, with the result that no oil will drip from the receptacle during its removal from the reservoir. As any foreign matter in the oil cannot leave the container 2, the accumulation of carbon on the burners of the stove or range will be reduced to the minimum.

While I have described the principle of the invention, together with the structure which I now consider the preferred embodiment thereof, it is to be understood that the structure shown is merely illustrative and that such changes may be made when desired, as fall within the scope of the invention as claimed, and while I have illustrated and described the closure as applied to the oil receptacle of an oil stove or range it is to be understood that the closure may be applied to dispensing receptacles generally.

What is claimed is:—

A closure of the character stated, comprising a cap having its annular wall screw threaded and provided in its circular wall with an axial opening, a tube extending through said opening and having its outer portion of less external diameter than its in-

ner portion to provide a shoulder bearing against the inner side of said circular wall and secured thereto, the tube being provided at its inner end with a valve seat, a stem extending through the tube and having a diameter less than the internal diameter of the tube, a valve secured to the inner end of the stem, a head secured to the outer end of a stem, a coil spring surrounding the outer tube portion and bearing against the said circular wall and head and constantly urging the valve in the direction of its seat, and a screen secured to the inner tube portion and surrounding the seat and valve and provided with a solid inner end.

In testimony whereof I hereunto affix my signature.

ALMOND W. PIPER.
